UNITED STATES PATENT OFFICE

2,444,213

ROTARY TURBINE

Harvey B. Weeks, Quincy, Mass.

Application October 17, 1944, Serial No. 559,012

2 Claims. (Cl. 60—41)

1

My present invention, in its broad aspect, has to do with improvements in rotary internal combustion engines of a turbine-like type, in which the explosive charge is delivered to pockets or chambers formed in the periphery of a rotor which has been given an initial impulse and is fired by a spark plug device to momentarily confine the explosive charge and then release it to reaction chambers in the stator or casing to thus exert a torque or active force against walls of the chambers or pockets in the rotor at an angle to the axis of rotation of the rotor to actuate the same, the reaction chambers of the stator being connected to successively exert a cumulative force against the rotor thereby to attain a greater operating efficiency from the fuel used. My present invention contemplates the provision of a rotor mounted on a drive shaft which is suitably supported, and a two part stator or casing in which the rotor operates. The rotor is provided with inclined vanes forming fuel pockets or chambers with which the combustible charge is directed and momentarily confined and ignited by a spark plug and then released into the chambers of the stator whose respective walls have walls which are successively slightly modified in inclination to react most efficiently against the vanes of the rotor; the chambers are connected to participate in delivering the explosive charge, and exhaust means are provided.

Other and equally important objects and advantages will be apparent from the detailed description and drawings, but it is to be understood that changes in form, size, shape, arrangement and construction of parts may be made provided same fall within the broad scope of my inventive concept and the scope of the appended claims.

In the drawings wherein I have illustrated a preferred form of my invention:

Figure 1 is a front elevation;

Figure 2 is a vertical section;

Figure 3 is a side view; Figure 2 having been taken on the line 2—2 of Figure 3, and

Figure 4 is a section taken on the line 4—4 of Figure 2.

In the drawings wherein like characters of reference are used to designate like or similar parts:

The numeral 1 designates the stator of my motor which is formed in two sections 2 and 3 bolted together as at 4 through meeting lips 5. The stator is carried and reinforced front and back by ribs 6 extending from the bearings 7 for the shaft 8 of my rotor 9. The stator 1 has spaced, angularly inclined chambers or reaction compartments 10 between its edge flanges 10a and the angles of inclination of the walls of

2

chambers 10 vary successively and slightly as will be apparent from Figure 2. Each chamber 10 has an outlet channel 11 at its rear end which channels communicate respectively with annular compartments 12, 13 and 14 about the stator and formed by casings 15. A boss 16 is formed on the stator which has a fuel injector connection 17 with a restricted outlet 18 for delivering the combustible charge, the restricted nozzle being directed angularly toward the inclined blades 19 of the rotor 9 and at an angle to the axis of the rotor, and a spark plug 20 is provided adjacent the fuel inlet or injector, and exhaust pipes 21 lead from the compartments 12, 13 and 14. The blades 22 of the stator between the chambers 10 have inclined walls. It will be noted that the fuel injector and spark plug are designed and arranged to deliver and explode the charge at a moment prior to delivery of the charge to the blades and chambers of the stator. A shoulder 23 is formed at the rear of each chamber 10 adjacent the outlet or exhaust channel 11.

The rotor 9 is formed with an annular rim 9a connected by spokes 9b to the hub 9c keyed as at 9d to the rotor shaft, and packing members 9e are provided between the edge flanges of the annular rim and the edge flanges of the stator. It will be seen that the construction is simple and sturdy and that the entire unit is assembled by the few bolts 4.

From the foregoing, it is believed that the operation and advantages of my invention will be apparent, but as previously emphasized, interpretation of the scope of my invention should only be conclusive when made in the light of the subjoined claims.

I claim:

1. A rotary internal combustion engine, comprising a rotor and a stator having diametrically opposed reinforcing ribs extending from the bearings for the rotor shaft to the upper periphery of the stator, the rotor and stator each having blades inclined in the same direction at an angle to the axis of the rotor, the chambers formed by the blades of the stator having exhaust channels leading to a common exhaust about the outer periphery of the stator, a fuel injection port in the stator and a spark plug adjacent thereto and designed to deliver and explode the charge at a moment prior to movement of the rotor to register the blades thereof with the blades of the stator, the angularity of the blades of the stator being slightly and successively modified to increase the efficiency of the motor, and each chamber of the stator has a shoulder adjacent the exhaust channel.

2. The invention as in claim 1 wherein the spark plug and fuel port are formed in a portion of the stator having no blades or chambers; the stator is formed with two sections bolted together and having ribs carrying journals for the rotor shaft; the rotor has an annular rim carrying the blades and spokes connecting the annular rim with the hub, and packing means are provided between the rotor and stator in the meeting edge flanges thereof.

HARVEY B. WEEKS.
